SPINNING SPINDLE

Gompei Kuwada, Maedani-mura,
Kawabe-gun, JapanApplication August 22, 1934, Serial No. 740,937
In Japan December 7, 1933

5 Claims. (Cl. 242—46.6)

My invention relates to a spinning spindle with the object of holding the bobbin to the spindle more tightly than by mere surface contact between them, of causing this grip to be tighter at higher speeds and in construction such that each integral part may be separately removable for facile replacement.

The reference is to be had to the accompanying drawing in which,

- 10 Fig. I is an elevation of the spindle,
Fig. II is a front elevation of the spring,
Fig. III is a side elevation of the same,
Fig. IV is a horizontal section of the same, and
Fig. V is a perspective view of the top of the
15 spindle wharve showing the circumferential and
vertical grooves into which the springs are positioned.

In this drawing 1 is the spindle wharve, 2 is the spring, 3 is the saddle to the spring 2, 4 is the cap to the wharve enclosing the springs 2 in place, 5 is the opening to the cap through which saddles 3 may protrude. In above drawing the same notation indicates the same part.

As shown by Fig. I the wharve of the spindle is made in two parts, the inner part being grooved circularly at the top and vertically along its side in several places, and the outer part made to cap over the inner part.

Figs. II, III and IV show the construction of the springs that are placed in the above mentioned grooves. These springs bear on their backs the saddles 3 which are metal pieces clasped over the said springs, the exterior of which is well rounded over. The cap 4 is so constructed that it fits tightly over the wharve and over the upper bar of the springs and moreover is provided with openings to admit the spring saddles to protrude beyond the exterior surface of the wharve cap.

As to the working of the spindle, when a bobbin is placed over the spindle the light resilience of the springs 2 presses the saddles 3 against the inside of the bobbin to ensure bobbin at the start to revolve along with the spindle, and as the speed increases the centrifugal force set up by the weight of the saddle causes the saddle to press more tightly against the inside of the bobbin; thus further ensuring the grip between the bobbin and the spindle.

In case any integral part of the spring or of the saddle becomes injured or worn by use, it may be easily replaced on removal of the cap 4.

Heretofore there have been spindles with only springs to assist in gripping the bobbin to the spindle but in such the edges of the springs rubbing against inside of the bobbin tends to cause

wear of the bobbin and effectual grip is lost.

Again there have been spindles in which free pieces enter in its assemblage which are allowed to fly out of the wharve by virtue of centrifugal force thus gripping the bobbin while the spindle is revolving, but in such a one by continued use lint and dust soon stuff up the aperture through which the free pieces protrude effectually hindering the action of the free pieces.

In my invention the springs are to provide the means of holding the bobbin lightly enough for its insertion and removal and for fixing the bobbin to its spindle so that the bobbin may revolve with the spindle from the very start when the latter is set revolving, a very essential point to be assured in spinning of yarn.

Having thus described the principle of the invention what I claim is:—

1. In a spinning machine spindle, a wharve comprising an inner member grooved circumferentially at its top and vertically along its side and an outer cap member fitting over the inner member, at least one T-shaped spring having its horizontal bar and its vertical bar positioned in the circumferential and vertical grooves of the inner member by the cap member, but having its vertical bar free to move within the vertical groove of the inner member.

2. In a spinning machine spindle, a wharve comprising an inner member grooved circumferentially at its top and vertically along its side and an outer cap member fitting over the inner member, a plurality of T-shaped springs having upper horizontal bars and vertical curved bars, said horizontal bars and said vertical bars being positioned respectively in the circumferential and vertical grooves of said inner member, the horizontal bars of said springs being held against the circumferential groove of the inner member but the vertical curved bars of said springs being free to move within the vertical groove of the inner member.

3. A spinning machine spindle as set forth in claim 1, in which the outer cap member of the wharve is provided with an aperture into which a part of the vertical bar of the spring may protrude.

4. In a spinning machine spindle, a wharve comprising an inner member grooved circumferentially and vertically along its side and an outer cap member fitting over the inner member, at least one T-shaped spring having its horizontal bar and its vertical bar positioned, respectively, in the circumferential and vertical grooves of the inner member by the cap member, said spring

having its vertical bar free to move within the vertical groove of the inner member, and metal saddle pieces secured to the vertical bar of said spring.

5. In a spinning machine spindle, a wharve comprising an inner member grooved circumferentially and vertically and an outer cap member fitting over the inner member, a plurality of T-shaped springs having their horizontal bars 5 and their vertical bars positioned in the circumferential and vertical grooves respectively of

said inner member, said springs having their horizontal bars held against the circumferential groove of the inner member by the cap member but having their vertical bars free to move within the vertical groove of the inner member, metal saddle pieces clasped over the vertical bars of the springs and the cap member being provided with apertures into which the saddle pieces on the vertical bars may protrude.
